(57) **CLAIM**

The ornamental design for a pro power center (oval display rack mount), as shown in the accompanying drawings.

DESCRIPTION

A portion of the disclosure of this design patent document contains material which is subject to copyright protection. The copyright owner has no objection to the facsimile reproduction by anyone of the patent document or the patent disclosure, as it appears in the U.S. Patent and Trademark Office patent files or records, but otherwise reserves all copyright rights whatsoever.

This application is a divisional of U.S. Design patent application Ser. No. 29/135,120, entitled "Pro Power Center" filed on Jan. 5, 2001 to the same inventor. This application is also related to the following Divisional Design Applications: Pro Power Center (Rectangular Display), Attorney Docket No. P1441; Tall Pro Power Center (Oval Display Table Mount), Attorney Docket No. P1443; Pro Power Center (No Display), Attorney Docket No. P1444; Pro Power Center (Oval Display Table Mount), Attorney Docket No. P1445.

FIG. 1 is a perspective view of a pro power center (oval display rack mount), in accordance with the present invention.

FIG. 2 is a plan view of a pro power center (oval display rack mount), in accordance with the present invention.

FIG. 3 is an underside view of a pro power center (oval display rack mount), in accordance with the present invention.

FIG. 4 is a side view of a pro power center (oval display rack mount), in accordance with the present invention.

FIG. 5 is a corresponding side view of a pro power center (oval display rack mount), in accordance with the present invention.

FIG. 6 is a rear view of a pro power center (oval display rack mount), in accordance with the present invention; and,

FIG. 7 is a frontal view of a pro power center (oval display rack mount), in accordance with the present invention.
